UNITED STATES PATENT OFFICE.

LOUISE TULLY, OF NEW YORK, N. Y., ASSIGNOR TO THE BUTTERICK PUBLISHING COMPANY, (LIMITED,) OF SAME PLACE.

DESIGN FOR A LADY'S OVERSKIRT.

SPECIFICATION forming part of Design No. 14,639, dated February 5, 1884.

Application filed December 26, 1883. Term of patent 3½ years.

To all whom it may concern:

Be it known that I, LOUISE TULLY, of the city, county, and State of New York, have invented and produced a new and original Design for a Pattern of a Lady's Overskirt, (numbered 9,011;) and I do hereby declare that the engraved prints accompanying this specification convey to any one accustomed to using paper patterns a clear understanding of how a garment made up by the pattern will appear.

The design shows a front drapery that exhibits a deep point at the right side, and is wider and shorter, with rounding lower cor-

ners to the left of the point, displaying draping plaits at its back edges and above the front edge of the point, and a deep oval back drapery that exhibits draping plaits at its front edges.

What I claim as my invention, and desire to secure by Letters Patent, is—

The design for a lady's overskirt, as shown in the engraved prints accompanying this specification.

LOUISE TULLY.
